UNITED STATES PATENT OFFICE.

ABNER G. GILLETTE, OF ATLANTA, GEORGIA.

TALC-PULVERIZER.

SPECIFICATION forming part of Letters Patent No. 390,852, dated October 9, 1888.

Application filed February 17, 1888. Serial No. 264,442. (No model.)

To all whom it may concern:

Be it known that I, ABNER G. GILLETTE, a citizen of the United States, residing at Atlanta, in the county of Fulton and State of Georgia, have invented a new and useful Talc-Pulverizer; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

This invention relates to machinery for pulverizing talc or steatite.

The invention obviates the difficulties experienced in attempting to grind or pulverize talc by the ordinary burr-stone or roller-mill, or by a stamping-mill process. These difficulties are due to the composition of the talc or steatite being such as to cause the stamp and roller mills above mentioned to only partially disintegrate it, and at the same time to pack it into a compact mass; or, in the case of the burr-mill, the substance has a tendency to pack in the furrows in the faces of the stones. All of these difficulties are obviated by my device, the details of which will be hereinafter fully described, and the parts thought to be new pointed out in the claims.

In the accompanying drawings, Figure 1 is an elevation, partly in section, showing the beaters, with proper pulleys and shafting for running the beaters in opposite directions, the feed-chute, and the outlet-flue. Fig. 2 is a central cross-section of Fig. 1, showing the construction and form of the interior. Fig. 3 is an end elevation showing the air-inlet and its regulating-gate and other details of construction.

In the figures like reference-marks indicate corresponding parts in the several views.

A is the cylinder, and B the beater-arms.

C is the inlet or feed-chute, and D is the outlet-flue.

The cylinder A is dentated on its inner surface, except a small portion near the bottom of the cylinder, which is preferably left smooth for ease in starting the machine, as, after stopping the machine, all material left therein will fall to the bottom, there impeding the

ready starting of the machine should the increased friction produced by contact of this material with dentations on the bottom be present; also, the dentations, if at the bottom, would fill up with material during the operation of the machine; and after further description of the device it will be readily seen that dentation would be almost wholly inoperative by reason of their position at the bottom and the fact that the material would not rebound therefrom to a sufficient extent to render dentations so placed fully operative on account of this filling up with material. This cylinder A is provided with heads or end pieces, a, in both of which are holes for the insertion of the shafts, and one has an opening and chute, C, for the introduction of the raw material, and the other an opening for the passage of air, which opening is enlarged or reduced by a damper, a'. (Best shown in Fig. 3.) In the interior, as shown in Figs. 1 and 2, are beater-arms B, which may be of any number. These beater-arms B have on their extremities the plates of metal b, set at an angle to the shaft, as shown. If found necessary for pulverizing material, these plates B may be set at any desired angle to a radial line. It is, however, preferable that the said plates be sloped slightly forward. The shafts of these beaters revolve in opposite directions and at a high rate of speed, as hereinafter set forth.

The operation of the device is as follows: The machine being started, the beaters revolving in opposite directions, the material is fed in sufficient quantity through the chute C, and the damper of the air-inlet is opened sufficiently to allow the air to enter in quantities requisite to blow the material which by the process becomes pulverous out of the flue D, which flue is long enough to prevent the centrifugal force from throwing out material which is not sufficiently fine for use. This flue generally extends to an upper or adjacent room, in which room the powdered talc is received. As the centrifugal force keeps the material against the inner dentated surface, and the angle of the plates b on the beater-arms B is such as to keep the bulk of the material in the center of the said dentated surface, and as the two sets of beater-arms revolve in an opposite direction, two annular

masses of material are kept in forcible contact, each mass being agitated and abraded by the inner surface of the cylinder, and the said two masses will grind against each other, producing friction sufficient to pulverize the entire mass in a short time. As the revolution of the beaters is rapid, and as the plates *b* are of sufficient size, a blast will keep the mass entirely free from pulverized material, the same being blown out of the flue *D* as fast as pulverized. On account of the angle of the plates the material will be thrown somewhat from side to side.

Having thus described my invention, what I claim as new, and desire to secure by Letters Patent of the United States, is—

1. In a talc-pulverizer, the combination of the beaters adapted to revolve in opposite directions, with their inclosing cylinder and its lining, said lining being formed of smooth sec-

tions located at the bottom of the cylinder, and dentated sections, forming the upper lining of the cylinder, substantially as set forth.

2. In a talc-pulverizer, the combination of the cylindrical vessel *A*, having dentated panels, forming the top of the cylinder, and smooth sections, forming the bottom, the beaters *B*, adapted to revolve in opposite directions, and having plates *b* set at an acute angle to the axis of said beaters, the feed-chute *C*, the air-inlet and its regulating-gate *a'*, and the outlet-flue *D*, all combined and operating substantially as shown and described, and for the purpose set forth.

In testimony whereof I affix my signature in presence of two witnesses.

ABNER G. GILLETTE.
